UNITED STATES PATENT OFFICE.

JOHN C. KOFF, OF BELLEVUE BOROUGH, PENNSYLVANIA.

UNIVERSAL JOINT.

1,343,728.

Specification of Letters Patent. Patented June 15, 1920.

Application filed November 20, 1919. Serial No. 339,411.

To all whom it may concern:

Be it known that I, JOHN C. KOFF, a citizen of the United States, and resident of the borough of Bellevue, in the county of Allegheny and State of Pennsylvania, have invented a new and useful Universal Joint, of which the following is a specification.

The object of this invention is to provide a power-transmission universal-joint which can be readily assembled and disassembled and which is composed of few, simple and easily manufactured parts. A universal-joint made upon the principle of the embodiment hereinafter described is particularly suitable for use in automobiles, where it is usually necessary to tear down the rear end in order to take apart the universal, whereas with this construction it can be disassembled and put back under the car without disturbing other parts. The device comprises two terminal members and an intermediate member successively pivoted on axes at right angles, the intermediate member being formed in sections which are collapsible for insertion and removal in one of the terminal members and locked in assembly by the pivot connection with the other terminal member. The nature of the device will be more fully understood from the following description, reference being had to the accompanying drawings, wherein:

Figure 1 is a side view showing the joint straight in full lines and flexed upon one of its pivots in dotted lines;

Fig. 2 is a side view looking at right angles to Fig. 1;

Fig. 3 is a cross-section on the line 3—3 of Fig. 1;

Fig. 4 is a cross-section on the line 4—4 of Fig. 1;

Fig. 5 is a longitudinal section on the line 5—5 of Fig. 2;

Figs. 6 and 7 are perspective views of the parts of the intermediate member, disassembled;

Fig. 8 is a side view of a terminal fork;

Fig. 9 is a side view of the intermediate member, collapsed;

Fig. 10 is a side view of the removable pivot pin; and

Fig. 11 is a side view of the other terminal member;

Figs. 8 to 11 showing the parts of the joint in approximate relations for assembling.

The numerals 1 and 2 indicate two shaft elements or the like, to one of which power is applied and through the joint transmitted to the other. The pivotal portions of these elements are herein termed the terminal members of the universal joint. One of the terminal members is preferably a fork 3, and the other member a hub-end 4, while the intermediate member 5 is preferably a frame-like part received between the arms of the fork and receiving in it the terminal member 4.

The arms of the fork are formed with opposed openings 6, in which cup bushings 7 are inserted from the interior, these bushings having out-turned flanges 8 on their inner, open ends, which abut against the inner faces of the fork.

The intermediate member is composed of two parts 9 and 9'. These parts are rectangularly U-shaped, and formed to fit one into the other, in reversed relation. Each part has an end wall 10 or 10^a and two side walls or limbs 11 or 11^a, the limbs 11^a being set in sufficiently from the extremities of the end wall 10^a to be received between the limbs 11. When the sections are assembled, the outer limbs 11 fit in the recesses beneath the projecting extremities of the end wall 10^a, abutting the shoulders 10^b formed thereby while the ends of the inner limbs 11^a abut the inner surface of the end wall 10.

The limbs 11 and 11^a are pierced by aligned pivot-pin holes 12 and 12^a, which register when the parts are fitted together. These holes receive the end portions of a pivot pin 13, the intermediate portion of which extends through the pivot hole 14 in the terminal member 4, said hole being lined by a bushing 15.

The end walls 10 and 10^a of the sections of the intermediate member bear pivot trunnions 16, 16^a, the axes of which are at right angles to the pivot-pin holes 12 and 12^a. Said trunnions pivot within the cup-bushings 7 in the fork member 3, when the joint is assembled.

The flanges 8 of the bushings lie between the fork and the ends of the intermediate member, thus locking the bushings against displacement in either direction, and also serving as bearing bosses. Oilers 17 are screwed into tapped openings in the outer, end walls of these bushings.

The outer surfaces 18^a of the inner limbs 11^a and the inner surfaces 18 of the limbs 11

are transversely curved on arcs concentric with the centers of the trunnions 16, 16^a. This enables the parts of the intermediate member to be turned relatively to each other into and out of assembly. When turned at right angles, as shown in Fig. 9, they can be slipped past each other, or collapsed, each pair of limbs passing at opposite sides of the end wall of the other section, in this way 10 shortening the distance between the ends of the trunnions so that the intermediate member can be introduced into or removed from the fork and the trunnions inserted in or withdrawn from their bearings. In the as- 15 sembed condition the pin 13 passing through the registering holes in the limbs locks the sections of the intermediate member together and their trunnions against escape from the bearings.

20 One end of said pin 13 is provided with a kerf 19 or other tool-receiving formation, and the opposite end is externally screw-threaded as indicated at 20 to engage corresponding internal threads in the hole of 25 one of the outer limbs 11. Said end of the pin also has an internally screw-threaded socket 21, the threads of which are of different pitch from the outside threads 20. From said socket extends a longitudinal in- 30 ternal lubricating channel 22, communicating with external channels 23, closed by the bushing 15. An oiler 24 has a stem 25 threaded to engage the socket 21, and when this oiler is screwed in with its shoulder 35 tight against the limb 11, it acts as a lock-screw to prevent the pivot-pin coming loose. The screw end portion of the pin 13 is reduced to form a shoulder 13^a which abuts against the inner side of the adjacent 40 limb 11^a, thus acting as a positive stop to prevent outward projection of the extremity of the pin, which would destroy the locking action of the oiler. The holes 12, 12^a in 45 these two limbs 11, 11^a are correspondingly smaller than the holes in the other two limbs.

All that is required to take the joint apart is to remove this oiler and unscrew, and take out the pivot-pin. This releases the 50 terminal member 8. The sections of the intermediate member can then be turned relatively to each other, collapsed and withdrawn from the fork.

While the preferred form has been de- 55 scribed in detail, it will be understood that the invention is not necessarily limited to the precise construction shown and that other equivalent forms may be designed by the mechanic.

60 What I claim as new is:

1. A universal joint comprising two terminal members and an intermediate member pivoted at right angles, characterized by the intermediate member comprising two 65 parts, each having a pivot portion for en-

gagement with one of the terminal members, which is a fork, said parts being collapsible so as to shorten the distance between said pivot portions whereby the intermediate member can be inserted in and 70 removed from the fork, and a removable pivot connection with the other terminal member which when in place prevents collapsing of said parts and locks the whole in assembly. 75

2. A universal joint comprising two terminal members and an intermediate member pivoted at right angles, characterized by the intermediate member comprising two parts each having a pivot portion for connection with one of the terminal members, said parts fitting one inside of the other and being collapsible for insertion and removal in said member and having registering pivot-pin holes in their overlapping 80 portions at right angles to said pivot portions, and a removable pivot connection engaging said holes and the other terminal member and locking said parts in assembly. 85

3. A universal joint comprising two terminal members and one intermediate member, the intermediate member comprising two substantially U-shaped parts fitting together and each having a trunnion on its end to engage one of the terminal members, 95 said parts being further provided on their limbs with transversely curved meeting surfaces whereby they can be turned and slipped past each other, said limbs having registering pivot-pin holes, and a removable pivot connection engaging said holes and the other terminal member. 100

4. In a universal joint, the combination of a fork terminal member, a frame-like intermediate member comprising two substantially U-shaped parts fitting together and each having a pivot portion at its end to engage the fork, said parts being further provided on their limbs with transversely curved meeting surfaces whereby they can be turned and slipped past each other, said limbs having registering pivot-pin holes, another terminal member inside said frame-like intermediate member, and a removable pivot connection engaging this terminal 115 member and said holes. 105

5. In a universal joint, the combination of two terminal members, an intermediate member comprising two parts each having a pivot portion to engage one of the terminal members, said parts fitting one inside of the other and being collapsible for insertion and removal in said member and having registering pivot-pin holes at right angles to said pivot portions, a removable 120 pivot-pin with oil ducts passing through said holes and the other terminal member, said pivot-pin having an external screw portion engaging threads in one of the parts and being further provided with a screw 125 130

socket having threads of a different pitch, and an oiler having a stem threaded to engage said socket and lock the pin.

6. In a universal joint, the combination 5 of a fork terminal member having opposed openings in its branches, an intermediate member comprising two fitting parts collapsible for insertion and removal and having trunnions on their ends and transverse 10 registering pivot-pin holes, another terminal member, a removable pivot-pin passing through this member and said registering holes, cup bushings in the openings of said fork member having flanges on their inner 15 open ends disposed between the fork arms and the ends of the intermediate member, and oilers in said bushings.

7. A universal joint comprising two ter-

minal members and an intermediate member pivoted at right angles, said intermediate member comprising two parts each having a pivot portion for connection with one of the terminal members, which is a fork, said parts overlapping each other and being adapted to be turned relatively to each other 25 and then collapsed so as to shorten the distance between said pivot portions, for insertion and removal in the fork, and having abutting portions which prevent collapsing except as the parts are so turned, 30 and being further provided with registering pivot-pin holes in their overlapping portions, and a removable pivot connection engaging said holes and the other terminal member and locking said parts in assembly. 35

JOHN C. KOPF.
